[57] CLAIM

The ornamental design for a bottle cap, as shown and described.

DESCRIPTION

FIG. 1 shows a side elevation view of my new design, with all other side elevation views being a mirror image thereof; FIG. 2 shows a top plan view thereof; and, FIG. 3 shows a side elevation view of the bottle cap of FIG. 1 mounted on a bottle.

The broken line showing of a bottle is for illustrative purposes only and forms no part of the claimed design. The bottom and interior of the bottle cap form no part of the claimed design.
